(57) **CLAIM**

We claim the ornamental design for a remote control, substantially as shown and described.

DESCRIPTION

FIG. 1 is a front view of a remote control of the present invention;

FIG. 2 is a back view thereof;

FIG. 3 is a left side elevation view of FIG. 1;

FIG. 4 is a right side elevation view of FIG. 1;

FIG. 5 is a top elevation view of FIG. 1, the bottom elevation view being a mirror image thereof;

FIG. 6 is a front perspective view thereof; and,

FIG. 7 is a back perspective view thereof.

FIGS. 1-7 show features of a remote control with broken lines. These features are for illustrating reference of environmental structure only and do not form any part of the claimed design.
